BLOWPIPE NOZZLE

Frank C. Geibig, Westfield, N. J., assignor, by
mesne assignments, to Union Carbide and Car-
bon Corporation, a corporation of New York

Application May 18, 1934, Serial No. 726,216

3 Claims. (Cl. 158—27.4)

This invention relates to blowpipe nozzles and particularly to multiple flame, fluid-cooled nozzles.

Heretofore such nozzles have been cast and the passages for conducting gases and cooling fluid have been drilled in the nozzle. Such a method of constructing the passages is relatively expensive and does not provide a sufficiently flexible arrangement of the passages for all types of nozzles, particularly for the multiple flame nozzles such as are used in welding machines, because the passages can be drilled only in straight lines and any change in the direction of the gas is usually abrupt which causes irregular flow of the gas streams and in turn produces a poorly shaped flame.

In such multiple flame nozzles the flame producing gases are distributed from the distributing chamber to individual gas flame-forming passages. In some nozzles it is impractical to locate the inlets of such drilled passages in the distributing chamber so that the pressure of the gas delivered to said chamber will be exerted equally in all of said inlets and distribute the gases equally among the individual flame-forming passages.

Where the cooling fluid passages and the gas passages are drilled in the nozzle, the greater portion of the volume of the nozzle is solid metal. That condition reduces the volume of cooling fluid which may be retained in the nozzle and circulated freely about the gas passages and the nozzle block adjacent to the flames, and it also increases the thickness of the metal which separates the gas passages from the cooling fluid passages and thereby reduces the cooling efficiency of the cooling fluid.

Therefore, among the objects of this invention is to simplify the construction of blowpipe nozzles and provide an improved method of construction which may be employed in different types of nozzles.

Another object of this invention is to distribute gas uniformly among a plurality of gas jets and to convey the gas from a distributing chamber to the jets in a smooth uninterrupted flow.

A further object of this invention is to provide an improved means for cooling the blowpipe nozzle and the gas passages therein.

The above objects and other novel features of this invention will be more clearly understood from the following description and accompanying drawing, in which:

Fig. 1 is a rear end elevation view of a blowpipe nozzle embodying this invention;

Fig. 2 is a cross-sectional view on line 2—2 in Fig. 1, looking in the direction of the arrows; and

Figs. 3 and 4 are, respectively, cross-sectional views on lines 3—3 and 4—4 in Fig. 2, looking in the direction of the arrows.

The principles of this invention are illustrated in the blowpipe nozzle N disclosed in the accompanying drawing.

The nozzle N comprises a nozzle block B having a set of preheating tips H and welding tips W connected thereto which are adapted to direct a plurality of preheating and welding flames 15 upon the work for preheating and fusing the portions of the metal to be welded together. Another tip P, supplied with a combustible gas mixture from a mixer M, is secured in the rear end of the block B for protecting the rear portion of the 20 puddle of weld metal from the air and for normalizing the weld. A combustible gas mixture such as a mixture of oxygen and acetylene is supplied to the preheating tips H and welding tips W from a gas mixer (not shown) which may be connected to the inlet I of a distributing chamber C in a distributor head D from which the gas is conducted through tubes T to the tips H and W. The tubes T and the block B are cooled by a cooling fluid which is circulated in a 30 jacket J.

The distributor head D and the nozzle block B are made of a good heat-conducting material such as copper or an alloy thereof. The parts are preferably cast and machined to receive the parts 35 cooperating therewith. Outlet passages 10 are bored through the bottom wall 11 of the distributing chamber C substantially equally distant from the center of the gas inlet I so that the velocity head of the gas entering the distributing chamber C will be substantially equal in all of the outlets 10 and thereby cause the gas to be transferred through each of the outlets with equal velocity to each of tips H and W.

In order to further assist in distributing the 45 gas uniformly among or with an equal velocity to the tips H and W and to facilitate smooth flow and uniform distribution of the gas stream within the chamber C, a dome or conical projection 12 is formed in the bottom of the chamber to direct 50 the gas smoothly to the outlet passages 10, while preventing or limiting the formation of side or eddy currents.

The outlet passages 10 in the distributor head D are counterbored to receive, the upper ends 55

of the gas tubes T and the lower ends of the tubes T are received in counterbores of the passages 13 bored in the block B which receives the shanks 14 of the tips H and W. The tubes T may be silver soldered in the counterbores in the distributor head D and in the nozzle block B.

As shown in Fig. 4, the outlet passages 10 from the distributing chamber C are arranged on a single circle concentric with the inlet I, and as shown in Fig. 2, the tip passages 13 in the nozzle block B are arranged in a straight line, and the respective passages 10 and 13 in the distributor head D and the nozzle block B are inclined at an angle to each other.

In order to connect the non-aligned passages 10 and 13 so that the gas may be transferred from one to the other without producing objectionable eddy currents in the gas streams, the tubes are made of yieldable material such as copper, or other suitable metal or alloy, which may be bent or flexed in the form of smooth or streamline curves between the non-aligned passages without causing collapse of the tubes and while maintaining the original cross-sectional area of the passages therethrough. Such construction provides a relatively inexpensive means of forming smoothly curved gas passages and a flexible arrangement of the gas jets in respect to the outlet passages leading from the distributing chamber C, without complicating the construction of the gas passages. For example, the arrangement of the tips or the flame-forming passages in the block B is not limited by the shape of the distributing chamber C because the individual tubes T may be bent to conform to the pattern of the tips selected, whether they be arranged in single or double rows, or circles, or other configurations.

The mixer M for the protecting tip P is supplied with oxygen and a combustible gas, such as acetylene, through tubes 15 and 16, respectively connected to the rear end of the nozzle block B. The gases are mixed in the mixer throat 17 to form the combustible mixture which is delivered to the protecting tip P.

The walls of the gas conducting tubes T are preferably made of relatively thin copper or other good heat-conducting material and are enclosed in the jacket J which comprises the bottom wall 11 of the distributor head D, the top wall 18 of the block B, and a sheet metal piece 19 silver-soldered or otherwise connected with a fluid-tight joint to the outer walls 20 and 21 of the distributor head D and the block B, respectively. The cooling fluid is supplied to the jacket J through an inlet tube 22 which extends through a bore in the rear end of the block B and delivers the cooling fluid adjacent to the top wall 18 of the nozzle block B near its rear end where it is subjected to its greatest amount of heat. The cooling fluid is conducted away from the top of the cooling jacket J by an outlet tube 23 which extends through a bore in the rear end of the block B and upward to the top of the jacket where it is provided with an inlet opening 24 which receives the cooling fluid from the jacket J. It will be noted that this construction provides an efficient cooling system, since the walls of the tubes T are made of relatively thin, good heat-conducting material about which a relatively large volume of water is freely circulated in intimate contact therewith and with the nozzle block B.

In order that the gas passages 13 and 10 in the block B and distributor head D may be maintained at a suitable temperature by the cooling

fluid, grooves or channels 25 and 26 are formed in each of these members adjacent to the side and end margins of the top wall 18 of the block B and the outer margins of the bottom wall 11 of the distributor head D. The block B is also provided with a passage 27 which extends between the grooves 25 on opposite sides of the block B and underneath the mixer throat 17 for preventing the gases which flow therethrough to the protecting tip P from being overheated.

The gas inlet tubes 15, 16 for the mixer M and the inlet and outlet tubes 22, 23 for cooling fluid extend upward from the rear end of the block B parallel with each other and are enclosed in a casing 28 which is secured to the block B.

While one embodiment of this invention is shown and described herein it will be understood that changes in the details may be made without departing from the scope of the invention as described in the appended claims. Certain features disclosed but not claimed herein form the subject matter of the copending applications of J. H. Bucknam, Serial No. 718,474 and Serial No. 728,133.

I claim:

1. A blowpipe nozzle comprising a nozzle block having a row of gas passages extending therethrough; said nozzle block having grooves formed therein, one on each side of said row of gas passages; a header having a gas distributing chamber therein; said distributing chamber having an inlet thereto and outlets therefrom; tubes connecting said outlets in said distributing chamber to said passages in said nozzle block; a cooling fluid jacket enclosing said tubes; said jacket comprising the bottom wall of said header, the top wall of said nozzle block and a metal wall secured to said header and the outer wall of said nozzle block; said block having a pair of bores extending through its rear wall; a cooling fluid inlet tube extending through one bore of said pair and adapted to discharge cooling fluid into said jacket adjacent to the top wall of the nozzle block; a cooling fluid outlet tube extending through the other bore of said pair into said jacket and having an opening adjacent to the top of said jacket; a mixer within the nozzle block, gas supply tubes for said mixer extending alongside said cooling fluid tubes; and a sheath secured to said block and enclosing said gas supply and inlet and outlet cooling fluid tubes.

2. A blowpipe nozzle comprising a nozzle block having a row of laterally aligned gas passages extending therethrough; a header having a gas distributing chamber therein; said distributing chamber having an inlet thereto and outlets therefrom; tubes of yieldable material connecting said outlets in said distributing chamber to said passages in said nozzle block; a cooling fluid jacket enclosing said tubes; said nozzle block having a gas mixer in its rear end and having channels for cooling fluid on each side of said mixer and extending lengthwise of said block on opposite sides of said row of gas passages; said block having a bore for cooling fluid extending between said channels and beneath said mixer; said block having a pair of bores extending through its rear wall, one on each side of said mixer; a cooling fluid inlet tube extending through one bore of said pair of bores and adapted to discharge cooling fluid into said jacket adjacent to the top wall of said nozzle block; and a cooling fluid outlet tube extending through the other bore of said pair of bores into said

jacket and having an inlet opening adjacent to the top of said jacket.

3. A blowpipe nozzle comprising a nozzle block having a row of gas passages extending therethrough; a header having a gas distributing chamber therein; said distributing chamber having an inlet thereto and outlets therefrom; tubes connecting said outlets in said distributing chamber to said passages in said nozzle block; a cooling fluid jacket enclosing said tubes; said nozzle block having a gas mixer in its rear end and having channels for cooling fluid on each side of said mixer and extending lengthwise of said block on opposite sides of said row of passages,

and adjacent thereto; said block having a bore for cooling fluid extending between said channels and adjacent said mixer; said block having a pair of bores extending through its rear wall, one on each side of said mixer; a cooling fluid inlet tube extending through one bore of said pair of bores and adapted to discharge cooling fluid into said jacket adjacent to said nozzle block; and a cooling fluid outlet tube extending through the other bore of said pair of bores into said jacket and having an inlet opening adjacent to the top of said jacket. 5 10
